EXTENSION SYSTEM FOR CURTAIN RODS

Filed Dec. 14, 1927

INVENTOR.
William C. Kenney
BY
Alvin Spear Jr.
ATTORNEY.

UNITED STATES PATENT OFFICE

WILLIAM C. KENNEY, OF CRANSTON, RHODE ISLAND, ASSIGNOR TO KENNEY MANUFACTURING COMPANY, OF CRANSTON, RHODE ISLAND, A CORPORATION OF RHODE ISLAND

EXTENSION SYSTEM FOR CURTAIN RODS

Application filed December 14, 1927. Serial No. 239,909.

In my present invention I am dealing with rod, rack or like hanging structures and related devices in which a variable spacing is desired for a rod or bar, whatever its use may be. The curtain rod affords a satisfactory basis for household example of the variant problems of supporting hangers at desired distances from a wall or the like.

The problem is a general one and has been variously dealt with in various lines, but taking the curtain rod as a convenient example, we have in ordinary usage the problem of spacing the rod or bar at a desired distance from a face, wall, ledge or window.

In all drapery work, it is important to arrange the draperies to fit as closely as possible to the window casing, but where a window shade is hung on the face of the window casing or where Austrian shades are used, it is necessary to project the draperies a varying distance from the casing, depending upon the amount of clearance needed.

My invention permits the use of a rod of short projection which can be positioned at varying distances from the window casing, according to circumstances, by merely using one or more extension pieces. This enables the dealer to furnish a variety of projections with only one stock of curtain rod, that is to say, the dealer need only carry a stock of rods of minimum projection and is still able to furnish any desired projection by merely adding extension pieces of the proper number.

Heretofore, the dealer has had to stock rods of various projection, in order to take care of these variations in projection, and this has meant that the dealer has had difficulty in maintaining the proper balance of stock in the various rod projections.

Moreover, single, double and triple rods may be arranged by the mere interchange of brackets, that is to say, a double rod may be made by the combination of two rods of standard projection and a double bracket. Likewise, a triple rod may be made by the combination of three rods of standard projection and a triple bracket.

My invention thus makes it possible for the dealer to furnish a variety of projections all from one standard projection, as well as per-

mitting the manufacturer to reduce manufacturing costs and stock by standardizing on one particular rod projection.

I am aware that in the case of brackets for double rods the spacing of the rods has been effected by making one of the integral arms of the bracket longer than the other so as to offset the outer rod and I am aware that the exposed portion of this arm has been made to simulate the form of the curtain rod end with which it connects after the usual manner of ferrule connections. My present invention while carrying out the old ferrule idea does so by providing independent unitary extensions for the rod end as distinguished from the old offset bracket and while it is an extension piece my concept makes it a unitary factor capable of inter-unit extension as desired for any kind of a curtain rod assembly whether single or plural, so that by the use of these units the spacing of the curtain rod or rods from the window may be made as desired.

My present concept thus involves a new factor or integer supplementary of old standard equipment but converting the old by its own new powers of inter-assembly into all of the several old stock styles and in addition some new ones.

My new factor is in fact a section of the rod itself but made for inter-engagement with the rod end preferably so as to give apparent continuity therewith. Such a device and its relation to the other old or standard parts will be shown in their several relations in the accompanying drawings. In these drawings:

Fig. 1 is a side elevation of an old single bracket and the elbow of a curtain rod supported by it.

Fig. 2 shows the same assembly stepped up by my unit.

Fig. 3 shows the same further offset by the use of two of my units.

Fig. 4 shows a pair of old standard brackets and rods converted by the use of my unit into a double fixture for an overdrapé.

Fig. 5 an extra spacing of the same.

Fig. 6 shows an old double bracket.

Fig. 7 a similar type triple bracket.

Fig. 8 an inner face view of one of my units.

Fig. 9 is a similar view of a pair assembled, and

5 Fig. 10 a double space unit.

I have taken as a basis of illustration an ordinary curtain rod 1 having a bend or elbow 2 of fixed or given length. The bracket 3 is an ordinary single bracket having an attaching arm 3¹ of ordinary length and adapted to receive the end of the elbow 2 of the rod 1.

For such standard parts I provide a unit or integer 4 which is preferably in form a short section of the same construction or contour as that of the rod 1. It is provided with an end tongue 4¹ which may be and preferably is of the same size, shape and construction as the tongue or arms 3¹ of the old brackets 3, 13 or 23. It is therefore not only capable of being assembled with the single rod end as in Fig. 2, but assembled as in Fig. 9 it constitutes a double rod end extension as in Fig. 3.

25 In Fig. 7 I have shown a simple form of bracket for a three rod curtain fixture. It will be understood that the bracket 13 may be substituted for the two brackets 3 shown in Figs. 4 or 5 or, for a three rod structure, the bracket 23 (Fig. 7) may be substituted for three single brackets. The form shown in Fig. 10 is simply a longer unit 14 which may be used if desired in place of the double assembly shown in Fig. 9.

35 It will thus be seen that by my invention I am able to use a standard curtain rod 1 of fixed uniform length elbow 2 and with the bracket 3 or any of the old multiple brackets 13 or 23 not only get any of the double or multiple curtain drape fixtures, but can modify any single, double or triple or other number equipment to give any spacing desired. I can do so by supplying the casual customer with a few extra pieces such as 4 to be used (or not) as the ultimate problem is finally 45 found to be when the curtains or other draperies are actually put up.

When the extension pieces 4 are to be used they may be applied as desired to the ends of the curtain rod or rods so as to form extensions thereof to give the proper spacing. This permits the curtain to be run on to the rod and draped around the elbow as desired as distinguished from the practice where the arm of the bracket is extended, in which 55 case the sides of the curtain have to be run in over the bracket and after the rod is in place.

The extensions may be made of any desired 60 configuration but preferably of course of the shape of the curtain rod itself of which it is to form an extension. Furthermore, various types of attaching means may be employed although that indicated is a satisfactory structure affording considerable

strength for the extensions. The frictioning devices may be of any type. The tongue form as shown is merely illustrated as an old accepted type but any other form or type may be substituted. Other modifications and variants as above indicated may be resorted to and differences in design and finish may be employed and all without departing from the spirit of my invention as indicated in the claims.

75 What I therefore claim and desire to secure by Letters Patent is:

1. In a curtain fixture for use with a curtain rod having an elbow end, a bracket having a prong and a bracket prong extension comprising a member telescopically engageable at one end with the prong of the bracket upon endwise movement in a straight line relative to the bracket prong and at its opposite end frictionally engageable within the elbow end of the rod upon endwise movement of said elbow end in a straight line relative thereto and when so engaged lying in the same plane with the bracket prong and the inner end of the rod elbow.

80 2. In a curtain fixture for use with a curtain rod having an elbow end, a bracket having a straight flat prong, and a bracket prong extension comprising a straight flat channeled member telescopically engageable at one end with the prong of the bracket upon endwise movement in a straight line relative to the bracket prong and at its opposite end frictionally engageable within the elbow end of the rod upon endwise movement of said elbow end in a straight line relative thereto and when so engaged lying in the same plane with the bracket prong and the inner end of the rod elbow.

85 3. In a curtain fixture for use with a curtain rod having an elbow end, a bracket having a straight flat prong having a locking tongue, and a bracket prong extension comprising a straight flat channeled member telescopically engageable at one end with the prong of the bracket and frictionally engageable with the locking tongue at one end and at its opposite end having a locking tongue frictionally engageable within the elbow end of the rod upon endwise movement of said elbow end in a straight line relative thereto, said extension when so engaged lying in the same plane with the bracket prong and the inner end of the rod elbow.

90 4. In a curtain fixture for use with a curtain rod having an elbow end, a bracket having a prong, and a bracket prong extension comprising a member having guide flanges inturned from its longitudinal edges forming opposed channels permitting said extension to telescope over the prong of the bracket at one end upon endwise movement in a straight line relative to the bracket prong, said flanges terminating short of the opposite

end of the extension and said extension beyond said flanges telescopicable with the elbow end of the rod.

5. In a curtain fixture for use with a curtain rod having an elbow end, a bracket having a prong provided with a locking tongue, and a bracket prong extension comprising a member having guide flanges inturned from its longitudinal edges forming opposed channels permitting said extension to telescope over the prong of the bracket at one end and frictionally engage the prong tongue, said flanges terminating short of the opposite end of the extension and being provided beyond 10 said flanges with a locking tongue frictionally engageable within the elbow end of the rod.

6. In a curtain fixture for use with a curtain rod having an elbow end, a bracket having a straight flat prong provided with a locking tongue, and a bracket prong extension comprising a straight flat member having guide flanges inturned from its longitudinal edges forming opposed channels permitting said extension to telescope over the prong of the bracket at one end and frictionally engage the prong tongue, said flanges terminating short of the opposite end of the extension and being provided beyond 25 said flanges with a locking tongue frictionally engageable within the elbow end of the rod, said extension when so engaged lying in the same plane with the bracket prong and the inner end of the rod elbow.

35 7. A curtain rod assembly adapted to support an elbowed rod, comprising a bracket having a straight prong and an extension piece frictionally engageable at one end with the elbow end of the rod upon endwise movement of said elbow end in a straight line relative thereto and at its other end frictionally engageable with a prong of the bracket upon endwise movement of said extension piece in a straight line relative to said bracket prong 40 and when so engaged being disposed in substantially the same plane as the bracket prong.

8. As a curtain fixture set for mounting at least two similar curtain rods having 50 elbow sections of equal length at varying distances from the opening to be curtained, a plurality of similar supporting brackets each having two spaced prongs of equal length, and a plurality of similar interengageable extension couplings adapted for interposition between said elbow sections and bracket prongs to provide an optionally interchangeable progressively extensible connection between said rods and brackets permissive of 55 variable projections of said rods from said brackets and from each other.

9. As a curtain fixture set for mounting at least two similar curtain rods having 60 elbow sections of equal length at varying distances from the opening to be curtained, a

plurality of similar supporting brackets each having two spaced prongs of equal length, and a plurality of similar interengageable extension couplings adapted for interposition between said elbow sections and bracket prongs to provide an optionally interchangeable progressively extensible connection between said rods and brackets permissive of 70 variable projections of said rods from said brackets and from each other, said bracket prongs having tongues, and said couplings having lateral guide flanges adapted for frictional engagement with said prong tongues and beyond said guide flanges having tongues 75 adapted for frictional engagement within the elbow ends of the rods.

10. As an optionally interchangeable progressively extensible connection between a curtain rod and a bracket, a coupling consisting of one or more units adapted for interchangeable interposition between the rod and the bracket and mutually cooperative with each other and with the rod and bracket to secure variable projections of the rod from the bracket, said units at one end telescopically engageable with the bracket and at their other end telescopically engageable with the curtain rod or with a similar unit.

11. As a curtain bracket set for mounting at least two similar curtain rods having 95 elbow ends of equal length at varying distances from the opening to be curtained, supporting brackets each having prongs of equal length, and extension units for variably spacing one of said rods a greater distance from the opening to be curtained than the included rod, said extension units each frictionally engageable at one end with an elbow of a rod and at its other end with a prong of a bracket.

12. As a curtain bracket set for mounting at least two similar curtain rods having elbow ends of equal length at varying distances from the opening to be curtained, supporting brackets each having prongs of equal length, and extension units for variably spacing one of said rods a greater distance from the opening to be curtained than the included rod, said extension units each frictionally engageable at one end with an elbow of a rod and at its other end with a prong of a bracket 105 and when so engaged disposed in substantially the same plane as the bracket prong of which it constitutes an extension.

13. As a curtain bracket set for mounting at least two similar curtain rods having elbow ends of equal length at varying distances from the opening to be curtained, supporting brackets each having prongs of equal length provided with a locking tongue, and extension units providing successive extensions for variably spacing one of said rods a greater distance from the opening to be curtained than the included rod, said extension units each comprising a member having guide flanges inturned from its longitudinal edges 115

dinal edges for telescopic engagement with the tongue of a bracket prong at one end, said flanges terminating short of the opposite end of the prong and said unit being provided 5 beyond said flanges with a locking tongue frictionally engageable with an elbow end of a rod.

14. As a curtain bracket set for mounting at least two similar curtain rods having elbow ends of equal length at varying distances from the opening to be curtained, supporting brackets each having prongs of equal length, and separable interengageable extension units providing successive extensions for variably spacing one of said rods a greater distance from the opening to be curtained than an included rod, the innermost unit of said assembly telescopically fitting a prong of a bracket, the outermost unit frictionally fitting within the elbow end of a rod, 10 and the unit interposed between said innermost and outermost units being frictionally engageable with each of them to provide therewith a rigid telescopic connection between a rod elbow and a bracket prong.

15. As a curtain bracket set for mounting at least two similar curtain rods having elbow ends of equal length at varying distances from the opening to be curtained, supporting brackets each having prongs of equal length, and separable channeled extension units having tongue and recess connections and providing successive interengageable extensions for variably spacing one of said rods a greater distance from the opening to be curtained than an included rod, the channel of the innermost unit of said assembly telescopically fitting a prong of a bracket, the tongue of the outermost unit frictionally fitting within the elbow end of a rod, and the unit interposed between said innermost and outermost units being frictionally engageable with each of them to provide therewith a rigid telescopic connection between a rod elbow and a bracket prong.

16. As a curtain bracket set for mounting at least two similar curtain rods having elbow ends of equal length at varying distances from the opening to be curtained, supporting brackets each having prongs of equal length, and separable interengageable extension units providing successive extensions for variably spacing one of said rods a greater distance from the opening to be curtained than an included rod, the innermost of said units being frictionally engageable with a prong of a bracket, the outermost of said units being frictionally engageable with an elbow of a rod, and the unit interposed between said innermost and outermost units being frictionally engageable with each of them to provide therewith a rigid telescopic connection between a rod elbow and a bracket prong which connection is disposed in substantially the same plane as the bracket

prong of which it constitutes an extension.

17. In a curtain support, means for mounting a plurality of similar curtain rods in spaced relation to each other comprising brackets each having a plurality of spaced rod supporting prongs of equal length, a pair of couplings each adapted to be engaged at one end with the end of a selected curtain rod and with one of said supporting prongs whereby to extend said rod a distance corresponding to the length of said coupling beyond the position said rod would occupy if supported directly by said prongs, and additional pairs of similar couplings each engaged at one end with a rod end and at its other end with a similar already mounted coupling, whereby to form an optionally interchangeable progressively extensible connection between said curtain rods and said brackets.

18. A plural curtain mounting comprising brackets having spaced rod supports for supporting at least two curtain rods having elbows of equal length at varying distances from the opening to be curtained with one of said rods directly carried by one of said rod supports, and a plurality of coupling members adapted to be detachably interposed between the other rod and a pair of said supports whereby to project said rod outwardly beyond the rod which is carried directly by said supports, and a pair of interengaged couplings adapted to be interposed between a third rod and a corresponding pair of said supports, whereby to project said third rod outwardly beyond said second rod.

In testimony whereof I affix my signature.
